CLAIM

The ornamental design for a apple simulating seat cushion, as shown.

DESCRIPTION

FIG. 1 is a top, front, and left side perspective view of an apple simulating seat cushion showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken line showing of a woman in FIG. 1 and straps in FIGS. 1–7 is for illustrative purposes only and forms no part of the claimed design.
